METHOD OF AND APPARATUS FOR CREAT-
ING AN ARTIFICIAL FEVER

Edwin C. Sittler, Dayton, Ohio, assignor to General Motors Corporation, Dayton, Ohio, a corporation of Delaware

Application April 30, 1936, Serial No. 77,250

8 Claims. (Cl. 4—163)

This invention relates to methods of and apparatus for creating an artificial fever.

Recently, apparatus has been developed for creating an artificial fever within patients by subjecting them to circulating air at elevated temperatures and humidity.

It is an object of my invention to simplify such apparatus to make it more compact, lower in cost, easier to manufacture, install, repair and take care of.

A more specific object of my invention is to provide a body treating apparatus wherein the air treating, circulating and humidifying means are built in a unit which is readily insertable into and removable from the apparatus as a unit for assembly and repair.

It is another object of my invention to provide an improved liquid evaporating means for such an apparatus which is free from scaling and corrosion troubles.

It is another object of my invention to provide an improved means for disposing of perspiration of the patient.

Further objects and advantages of the present invention will be apparent from the following description, reference being had to the accompanying drawings, wherein a preferred form of the present invention is clearly shown.

In the drawings:

30 Fig. 1 is a vertical longitudinal sectional view through one form of my improved apparatus;

Fig. 2 is an enlarged sectional view taken along the line 2—2 of Fig. 1;

Fig. 3 is a sectional view taken along the line

35 3—3 of Fig. 1;

Fig. 4 is a sectional view taken along the line

4—4 of Fig. 2;

Fig. 5 is a sectional view taken along the line

5—5 of Fig. 2;

40 Fig. 6 is a horizontal sectional view taken through the cabinet looking down upon the air circulating and air treating devices;

Fig. 7 is a sectional view taken along the line

7—7 of Fig. 6; and

45 Fig. 8 is a wiring diagram for the air circulating and air treating means.

Brief description.

Briefly, I have disclosed a cabinet having walls 50 formed of a treated fibrous product having a removable wall at one end which leaves an opening which receives a wheeling couch which is normally positioned within the enclosure. The wheeling couch is provided with a head rest outside the enclosure formed of a slatted structure

which has a collecting pan and basin beneath it for collecting perspiration from the head. The wheeling couch is provided with a comfortable air or sponge rubber mattress. The removable wall is provided with a notch for receiving the 5 neck.

Within the enclosure above the wheeling couch is an inclined baffle having apertures at its upper end and being spaced from the end wall of the enclosure at the lower end which is opposite to 10 the end having the removable wall and the head portion of the wheeling couch. Supported on this baffle is an air circulating and air treating unit which is insertable and removable into position as a unit through an adjacent door. This treat- 15 ing unit includes a humidifying device which includes a receptacle kept filled with liquid by a constant level liquid supply device. This receptacle normally rests directly beneath a radiant heater provided with a reflector for direct- 20 ing radiant energy onto the surface of the liquid.

The enclosure

Referring now more particularly to the drawings, there is shown in Fig. 1 an enclosure or 25 cabinet generally designated by the reference character 20 having a bottom wall 22 formed of an upper layer 24 of moisture proof pressed wood or other suitable moisture proof molded composition and a bottom layer 26 of a suitable 30 cellular insulating material such as a pressed fibrous insulating material such as "Cellotex", or balsa wood. As is better shown in Fig. 2, the side walls 28 and the top wall 30 are formed of a relatively heavy layer 32 of a structural insulating 35 material such as compressed fiber board or balsa wood provided on either side with a thin sheet 34 of an impervious moisture excluding molded composition material such as pressed wood.

The bottom wall 22 is joined to the side walls 40 28 and the rear wall 44 by sheet metal angle members 36, 38, and 46 respectively, while the top wall 30 is fastened to the side walls by sheet metal angle strips 40 and 42.

These walls are fastened to the angle strips by 45 screws, such as the screw 92 as shown in Fig. 5, that extend through drilled passages in the metal strips, such as the strip 40, and the layers 32 and 34 of the side wall 28 for example, and thread into a nut 94 provided with barbs 96 for engaging 50 the inner face of the wall to prevent the rotation of the nut. In order to prevent the body of the patient from becoming scratched or burned by contact with one of these nuts, each of the nuts 55 is covered with a rubber boot 98 which substan-

tially entirely surrounds both faces of the nut so that the boot is tightly held in position by having one side clamped between the nut and the side wall. This provides a sturdy construction 5 which facilitates assembly.

The cabinet is supported by sheet metal legs 48 provided with glides 50 at their lower ends which are connected to the legs by a threaded connection for carefully adjusting the height for providing the cabinet with a perfect support. A lock nut 52 is provided for locking the glides in their properly adjusted position.

The wheeling couch

15 Within the enclosure, there is provided a wheeling couch generally designated by the reference character 54 which couch includes side rails 56 and 58, each provided with a groove on its inner face for receiving the edges of a supporting board 20 60 of multi-ply wood. At the inner end nearest the wall 44, each of these rails is provided with a recess which receives a fixed castor 62 provided with a large rubber tired roller which rests upon the bottom wall 22 of the enclosure. The board 25 60 normally supports an air or sponge rubber mattress which extends between the side rails from one end of the board 60 to the other. The head end of the board 60 is provided with a cross member 64 which extends between the side rails 30 56 and 58 and is provided with rubber sealing gaskets 66 at the bottom and side edges thereof for making sealing engagement with the bottom wall 22 and the side walls 28.

Fastened to the side rails 56 and 58, as well 35 as to the connecting strip 64, are two brackets 102. Each of these brackets is provided with a bottom face 104 to which is attached a metal leg 106 provided with a fixed castor 108 at its lower end. These legs 106 are connected by a tie rod and 40 spacer tube 110 for rigidity. The brackets 102 also support a very shallow metal pan 112 which supports a metal grating or grille work 114 upon which a pillow, provided with a rubberized cover, is normally provided for supporting the head of 45 the patient. The pan 112 receives the perspiration from the head of the patient and is provided with an outlet 116 placed directly over a flanged receiving basin 118 which is held by a hoop 120 welded to the freely movable end of an arm 122 50 which is pivoted to one of the brackets 102 by the pivot pin 124. The brackets 102 also serve as handles for pulling the wheeling couch 54 from the enclosure. The wheeling couch is locked in place by the spring hood type fasteners 126 which 55 are loosely connected to each of the legs 40 at the head end of the cabinet and which may be hooked over extensions 128 from the brackets 102 in order to securely hold the wheel couch in the enclosure.

The slidable wall

The top of this cross strip 64 is provided with a rubber sealing gasket 68 for making sealing engagement with the slidable neck wall 70. 65 This neck receiving wall is provided with a kerf at its side edges, each of which is lined with a sheet metal member 72 as is best shown in Fig. 3. This sheet metal member extends entirely across the edge portions and folds down upon the back 70 and front sides of this slidable neck receiving member to provide a metal bound edge. The kerf provided in each of these metal bound edges receives a slide-way 76 formed as a flanged edge of a vertical sheet metal side member 78, one of 75 which is fastened at the front edges of each of

the side walls. This member 70 is supported by spring type sash pulls designated by the reference character 80 recessed in the side walls adjacent the slidable neck receiving wall 70. The wall or member 70 is provided with stops 71 for 5 limiting its normal upward movement. This wall 70 is provided with handles 82 and a notch 84 for receiving the neck of the patient. This notch is provided with a kerf which receives a U-shaped rubber strip 86 which extends in the kerf around 10 the edge of the notch so that it may fit the neck of the patient with a sufficient tightness to prevent the escape of air from the enclosure. This rubber is readily removable and is held in place by the kerf and by large headed pins 90 which 15 extend through the rubber and through the wall 70.

The front edges of the top wall 30 and the side walls 28 which meet the slidable wall 70 are provided with rubber gaskets 130 and 132 which are 20 in the form of an extruded strip which is key shaped in cross section. In addition, in order to hold the slidable wall 70 tightly against these gaskets, there are provided brackets 134 fastened to the side walls which are provided with hand 25 screws 136 for clamping the slidable wall 70 tightly against the rubber gaskets. Adjacent one of the clamps is a second bracket 138 which is provided at its outer end with a round supporting disc 140 for supporting an ordinary propeller type 30 fan for directing a blast of air at the head of the patient.

Side doors

Nearest the head end of the cabinet, upon opposite sides, there are provided sliding doors 144 and 146. Each of these doors has an outer metal face 148 provided with upper and lower flanges 150 and 152 which are received within metal strips 154 and 156 fastened to the side walls of the cabinet by a bolt construction like that shown in Fig. 5. These metal faces of the doors are lined with an inner layer 158 of an insulating board and an inner face 160 of a thin molded sheet material which is impervious to moisture, similar to that used elsewhere throughout the cabinet. 45 These doors are each provided with handles 162 on the outer faces and with rubber stops 164 which extend into the openings 166 and 168 in the side walls 28, which openings are covered by the doors 146 and 144 respectively. Each of these 50 openings is lined with a wooden frame 170 which is covered by a molding 172 provided with a recess for receiving a strip of felt 174 extending entirely around the molding for making sealing engagement with the door to seal the door opening when the door is closed. These doors provide ready access for tending to and viewing the patient during the treatment.

Rear door and baffle

In the upper portion of the rear wall of the cabinet there is provided a door 176 normally positioned within the door opening 178 in the rear wall 44. This door 176 is supported by hinges 180 provided at its lower edges and is held in 65 closed position by a door latch 182 at its upper edge. Within the enclosure on opposite sides of the upper portion of the walls there are provided upper and lower strips 184 and 186 which between them, form a groove for slidably receiving 70 a baffle member 188 provided with apertures 190 at its head end. This baffle member is preferably formed of a molded moisture impervious sheet material such as pressed wood. The door 176 and the door opening 178 are positioned in alignment 75

with this baffle 188 so that the baffle may be withdrawn from the enclosure through the door opening 178 when the door 176 is open. This baffle extends into contact with the top wall 30 5 at the head end of the cabinet very close to the slidable wall 70. It is at this end that the apertures 190 are located. This baffle 188 divides the interior of the enclosure into a body compartment 192 where the wheeling couch supports the 10 patient and an upper compartment 194 which forms an air circulating passage. The baffle 188 terminates short of the door so as to allow an air circulating space between it and the door 15

Air treating unit

15 The lower portion of the baffle 188 is provided with a sheet 196 of high temperature insulating material and the adjacent side and top walls are likewise provided with sheets 198 and 202 of high 20 temperature insulating material. Resting upon the sheet 196 of high temperature insulating material is an air treating unit 204 which is sufficiently small in size that it may be readily inserted and removed through the door opening 25 178. This air treating unit has a sheet metal base 206 which rests upon the sheet 196 and has a vertical face plate 208 extending vertically upwardly from the sheet metal base 206. This face plate 208 is provided with a flange 210 at its upper edge for making sealing contact with the top sheet 202 of high temperature insulating material. At the sides, this plate 208 makes contact 30 with side plates 212 and 214 for making sealing engagement with the side of the air circulating 35 passage 194.

Thus, when the air treating unit is in position, all the air must flow through the aperture 216 formed in the center of the plate. Directly behind this aperture 216 is an electrically driven propeller type fan 218 provided with a vibration absorbing mounting. This fan draws the air from the body treating compartment 192 through the aperture 216 and over the heating and humidifying units behind the face plate 208 and thence 40 forces the air up through the air circulating passage 194 to the apertures 190, through which it is discharged back into the body treating compartment 192 above the chest of the patient. This 45 circulation is preferably at a rate of about 425 50 cubic feet a minute, but this may be varied upwardly or downwardly, as desired.

The vaporizing unit

At the right of the motor driven fan 218, there 55 is provided a humidifying or vaporizing unit 220 which includes a metal receptacle 222 which rests upon a sheet 224 of high temperature insulating material supported upon flanges 226 and 228 which extend rearwardly from the face plate 208. 60 Directly above the receptacle is a reflector 230 with a polished inner surface so shaped as to direct radiant energy onto the surface of the liquid within the receptacle 222. This reflector 65 may be formed of polished anodized sheet aluminum and may be covered with sheet asbestos. Beneath this reflector and above the level of the liquid in the receptacle 222 are two electric heaters 232 and 234 which are in the form of round bars which extend from insulated supporting 70 members 236 mounted at opposite ends of the reflector 230. These ends of the reflector are formed of enlarged plates 238 which are provided with slots 240 which receive supporting pins 242 for detachably supporting the reflector.

75 The receptacle slips through an opening in the

front plate 208 and has a tray front 244 which closes the opening when the tray or receptacle is in position. The front of the receptacle is provided with a tube 246 which is connected by rubber or other flexible tubing 248 to a tubular connection 250 which extends through the high temperature insulating sheet 198 and the side wall 28 to the exposed receptacle of a constant level supply means 252 which includes a bracket fastened to the outside of the cabinet provided 10 with an exposed receptacle for liquid which receives an inverted bottle supported above the bottom of the receptacle. By this simple scheme, a constant level of water is provided for the receptacle 222. 15

Upon the opposite side of the face plate 208 is fastened a humidistat having its adjusting means accessible from the outer face of the face plate 208, whereby the humidity may be regulated from 10% to 100% relative humidity. This humidistat controls the operation of a relay 256 mounted upon the base 206 which in turn controls the energization of the electric heaters 232 and 234. At the rear of the base is provided an electric strip heater 258 which is provided with fins so 25 as to readily heat the air which is circulated by the motor driven fan 218. A thermostat 264 is provided either on the base with an accessible adjustment extending through the face plate or outside of the cabinet. Preferably the thermostat is placed on the outside of the cabinet with a thermostatic bulb directly in front of the opening 216. This thermostat preferably has a range of from 100° or 120° to 195° F. 30

The electrical connections between these units 35 are shown in the wiring diagram of Fig. 8 which shows that electrical energy is supplied through conductors 260 and 262 under the control of manual switch 266. The fan 218 is connected by the conductors 268 and 270 across the conductors 40 260 and 262, while the electric heater is connected in series with the thermostat 264, but in parallel with the fan 218 by the conductors 272, 274 and 276. The humidistat 254 is connected in series with the relay coil of the relay 256 by the 45 conductors 278, 280 and 282. The heaters 232 and 234 are connected in series with separate contacts of the relay 256 by the conductors 284 and 286. 50

In operation, water is kept at a constant level 55 in the receptacle 222 by the inverted bottle apparatus 252 and the relay 256 is opened and closed by the humidistat 254 which is preferably set under ordinary conditions to energize the relay when the humidity falls 35 or 40%. The 60 closing of the humidistat 254 and the energization of the relay 256 closes the circuit through the heaters 232 and 234 which applies radiant energy to the surface of the liquid in the receptacle 222 so as to evaporate the liquid, usually water, in 65 the receptacle in order to supply humidity to the air which is circulated by the fan 218 whenever the switch 266 is closed.

This particular vaporizing apparatus is free 70 from ordinary troubles of other types of electrical evaporating apparatus because the heaters are not immersed in the liquid and therefore are not troubled by corrosion or covered by scale or by any impurities in the liquid. Thus, any lime in the water will merely fall to the bottom of the 75 pan and may be cleaned out by removing the receptacle without disturbing the electrical heaters.

The thermostat 264 is set ordinarily at about 150° F. during the period in which the fever or 75

- high temperature condition of the patient is being developed. After the maximum patient temperature desired is reached, the thermostat may be adjusted to energize and deenergize the heater 5 258 at lower temperatures in order to maintain the desired elevated temperature of the patient. Normally this setting is about 140° F. This apparatus is capable of rapidly elevating the patient's temperature to the maximum permissible 10 limit with relatively little discomfort and to maintain such an elevated temperature in the body. This apparatus may also be used in conjunction with a Dr. Elliot apparatus for aiding temperature rise and maintenance and also for local 15 high heat production at the same time of general fever incidence.
- Repairs or attention to this air treating unit 204 may be made by readily removing the entire unit.
- 20 While the form of embodiment of the invention as herein disclosed, constitutes a preferred form, it is to be understood that other forms might be adopted, all coming within the scope of the claims which follow.
- 25 What is claimed is as follows:
1. A body treating cabinet including walls forming an enclosure for enclosing and supporting a body, a baffle extending laterally across the enclosure dividing said enclosure into a lower body compartment and an upper compartment directly above the body compartment, said upper compartment containing an air treating unit, said air treating unit including means for circulating air through the body compartment and the upper compartment and means for changing the temperature and the amount of vapor in the air.
  2. A body treating cabinet including walls forming an enclosure for enclosing and supporting a body, a baffle extending laterally across the enclosure dividing said enclosure into a lower body compartment and an upper compartment directly above the body compartment, said upper compartment containing an air treating unit, said air treating unit including means for circulating air through the body compartment and the upper compartment and means for changing the temperature and the amount of vapor in the air, said enclosure being provided with a door in alignment with the air treating unit.
  3. A body treating cabinet including walls forming an enclosure for enclosing and supporting a body, a baffle extending laterally across the enclosure dividing said enclosure into a lower body compartment and an upper compartment directly above the body compartment, said upper compartment containing an air treating unit, said air treating unit including means for circulating air through the body compartment and the upper compartment and means for changing the temperature and the amount of vapor in the air, and means located outside the enclosure for supplying a liquid for vaporizing purposes to said air treating unit.
  4. A body treating cabinet including walls

forming an enclosure for enclosing and supporting a body, a baffle extending laterally across the enclosure dividing said enclosure into a lower body compartment and an upper compartment directly above the body compartment, said upper compartment containing an air treating unit, said air treating unit including means for circulating air through the body compartment and the upper compartment and means for changing the temperature and the amount of vapor in the air, said air treating unit being insertable and removable as a unit.

5. A body treating cabinet including walls forming an enclosure for enclosing and supporting the body, a baffle in the enclosure for dividing the interior of the enclosure into a body compartment and an air circulating passageway, a unitary air treating and circulating unit connected in air circulating series arrangement with said passageway, said unit being insertable and removable from the enclosure as a unit.

6. A body treating cabinet including walls forming an enclosure for enclosing and supporting the body, a baffle in the enclosure for dividing the interior of the enclosure into a body compartment and an air circulating passageway, a unitary air treating and circulating unit located in said passageway, said unit being provided with a dividing member having an opening therein for the circulating air, said dividing member extending into sealing engagement with the walls of the passageway, said unit having an air circulating means in series with said opening for circulating air from the body compartment through said passageway, said unit having an air treating means in said passageway, said dividing member, said air circulating means and said air treating means being structurally connected together to form a unit.

7. A body treating cabinet including walls forming an enclosure for enclosing and supporting the body, a baffle in the enclosure for dividing the interior of the enclosure into a body compartment and an air circulating passageway, a unitary air treating and circulating unit located in said passageway, said unit being provided with a dividing member having an opening therein for the circulating air, said dividing member extending into sealing engagement with the walls of the passageway, said unit having an air circulating means in series with said opening for circulating air from the body compartment through said passageway, said unit having an air treating means including a receptacle adapted to contain a liquid, and a means for directing radiant energy upon the surface of the liquid.

8. A body treating means including walls forming an enclosure for enclosing and supporting a body, means for heating the body within the enclosure, a support outside the enclosure for supporting the head of the body, said support being provided with means for collecting perspiration from the head.

EDWIN C. SITTLER. 65
